UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

COOK STOVE.

Application filed October 6, 1920. Serial No. 415,177.

To all whom it may concern:

Be it known that I, RUDOLPH HOFFMAN, a citizen of the United States, residing at Kankakee, in the county of Kankakee and State of Illinois, have invented certain new and useful Improvements in Cook Stoves, of which the following is a specification.

The invention relates in general to cook stoves and more especially to the means for swingably mounting the oven door or doors upon the stove.

The principal aim of the invention is to provide an improved built-in hinge construction which is particularly adapted for use in a stove constructed of sheet metal in that it obviates the necessity of employing any cast parts.

A further object of the invention is to provide a construction of simple character, efficient in operation, durable and presenting a neat and ornamental appearance.

The objects of the invention thus generally stated, together with other and ancillary advantages, are attained by the construction and arrangement shown in the accompanying drawings forming part hereof in which Fig. 1 is a perspective view of a cook stove embodying the invention. Fig. 2 is a fragmentary vertical sectional view through the stove and through the hinge at one side of one of the stove ovens. Fig. 3 is a fragmentary perspective view of the stove frame to which the hinge is applied. Fig. 4 is a fragmentary perspective view of the lower corner of the door embodying certain portions of the hinge. Fig. 5 is a perspective view of one of the hinge plates detached. Fig. 6 is a perspective view of a housing for the hinge parts. Fig. 7 is a fragmentary sectional view through the oven door jamb and a portion of the hinge. Figs. 8 and 8^a are fragmentary perspective views illustrating details of the hinge construction. Fig. 9 is a fragmentary transverse sectional view showing in particular the location of the door counterbalancing means.

The stove to which the invention is herein shown as applied, comprises two superimposed ovens 8 and 9 each closed by means of a door 10 and mounted for swinging movement upon the stove by means of hinges designated generally 11. The stove to which the invention is particularly applicable, is constructed almost wholly of sheet metal. Thus the oven section proper is made from

sheet metal and has a forward frame 12 having an intermediate cross bar 13 dividing the oven section into the two compartments providing the ovens 8 and 9. The doors 10 are also constructed for the most part of sheet metal as particularly set forth in my copending application Serial No. 409,771. Thus each of the doors comprises a rectangular frame 14 formed of strips of metal bent into channel form so as to provide an outer channel wall 15 and an inner channel wall 16. The outer channel walls 15 of the door frame 14 are provided with rigid reinforcing bars 17. The forward oven frame 12 together with the cross piece 13, it will be seen, provides the jambs for the doors 10. If desired, these jambs may be shaped to provide rabbet grooves 18 for the reception of the outer inner edges of the doors and thus form an effective seal when the doors are in closed position.

The means for swingably mounting the doors 10 for the ovens 8 and 9 are the same in both cases so that only one hinge construction need be described. Such construction comprises a hinge member 19 rigid with the door and a hinge plate 20 secured to the door frame.

The hinge member 19 consists of a sleeve 21 mounted upon a projecting portion 22 of one of the reinforcing bars 17, herein the bar for the lower portion of the door frame 14. To this end, the bar 17 for the side portion of said frame 14 is apertured as at 23 and through this aperture the portion 22 extends beyond the outer channel wall 15 of the door frame. Said portion 22 carries sleeve 21, the latter being made of an internal diameter to fit snugly over the portion 22. The sleeve is retained in position by bending the portion 22 at right angles, providing an arm 24 which preferably extends upwardly, in the closed position of the door, for a purpose which will later appear.

The plate member 20 is secured to the side bar of the frame 12 of the oven, as by means of bolts 25, and is shaped to provide a bearing 26 fitting neatly over the sleeve 21 which latter constitutes a journal for the door.

For the purpose of counterbalancing the weight of the door to prevent its sudden descent into its open position, I preferably provide spring means consisting of a coiled

expansion spring 27 anchored at 28 so as to be located externally of the oven and connected to the arm 24. Herein the spring means is located within the hollow side wall 5 of the oven (Figs. 2 and 9), which may be suitably apertured to permit of access to the interior of the wall. By thus locating the spring means externally of the oven it is removed from the intense and consequent injurious heat of the oven. To permit of the swinging movement of the arm 24 inwardly beyond the frame 12, the latter is apertured as at 29, the plate member 20 of the hinge being also cut away as at 30 10 for this purpose. Preferably the spring means for the door is so arranged that when the door is swung into its open position (broken lines Fig. 2) the arm 24 will be swung into or slightly beyond dead center 15 with reference to the spring 27 so that in this position the spring means shall not effect a closing of the door.

For the purpose of limiting the downward swinging movement of the door the bars 17 at 25 the sides of the door frame 14 are provided with downwardly extending fingers 31. Each finger is adapted, as the door is swung into its open position, to enter a slot 32 (Figs. 3 and 7) the upper wall of which 30 is so arranged as to form a stop 33 with which the finger is adapted to engage when the door reaches its horizontal position.

For the purpose of enclosing the hinge parts, I provide a housing 34 shaped to permit of the swinging movements of the arm 24 and of sufficient length to enclose the hinge plate 20. Preferably the housing is secured in position by means of the bolts 25 which secure the plate 20 in position on 40 the frame 12.

To facilitate the operation of the door from its closed to its open position and vice versa, it may be provided, as is usual, with a handle 35 of any preferred construction.

It will be seen that I have produced a 45 built-in hinge construction which may be constructed without the use of castings; which is of a simple character so that it may be cheaply manufactured; which is efficient in operation, and which presents a neat and ornamental appearance.

While the invention is herein set forth with considerable particularity, it is contemplated that various changes may be made 55 in the details of construction and arrangement without departing from the spirit and scope of the invention as expressed in the following claims.

I claim as my invention:

1. In a cook stove or the like, the combination with a door frame, of a door constructed of sheet metal and having a frame with a pair of relatively flat lateral projections one at each side near the lower edge 60 of the frame and rigid therewith, means

at opposite sides of the stove frame forming bearings, and cylindrical members on the outer ends of said projections forming journals adapted to engage in said bearings.

2. In a cook stove or the like, the combination with a door frame, of a door constructed of sheet metal and having a frame with a pair of lateral projections one at each side near the lower edge of the frame and rigid therewith, said projections having relatively sharp corners, means at opposite sides of the stove frame forming bearings, cylindrical members on said projections forming journals adapted to engage in said bearings, the free end of one of said projections being bent at right angles, and spring means connecting the free end of the arm thus formed normally tending to hold the door in its closed position.

3. In a cook stove or the like, the combination of an oven and a door therefor constructed of sheet metal, said oven having a frame formed of sheet metal providing a jamb for the door and said door having a frame also formed of sheet metal providing projecting side walls, the outer side walls of said door frame having rigid reinforcing bars extending beyond the lower edge of the door to form stop fingers, journal members rigid with said bars, bearing plates secured to the oven frame and adapted to receive said journal members, and spring means for closing said door, said oven frame having a slot in its forward wall for receiving said stop finger on the door one wall of which slot is adapted to be engaged by said finger so as to limit the downward movement of the door.

4. In combination with a frame providing a jamb, a door comprising a frame constructed of sheet metal having walls projecting from the edges thereof having associated therewith rigid reinforcing bars, the opposite side bars being of a length adapted to extend beyond the lower edge of the door and having apertures therein near their lower ends and the bottom bar having lateral extensions adapted to pass through said apertures in the side bars, bearing plates secured to the oven frame and adapted to receive said lateral extensions on the door whereby to mount the door for swinging movement, said downwardly extending portions of the side bars of the door constituting stop fingers adapted to engage with the oven frame to limit the downward swinging movement of the door.

5. In combination with a frame providing a jamb, a door comprising a frame constructed of sheet metal and bent to provide outer edge walls, said walls having associated therewith rigid reinforcing bars, the opposite side bars being of a length adapted to extend beyond the lower edge of the door and having apertures therein near their

- lower ends, and the bottom bar having lateral extensions adapted to pass through said apertures in the side bars, bearing plates secured to the oven frame and adapted to receive said lateral extensions on the door whereby to mount the door for swinging movement, said downwardly extending portions of the side bars of the door constituting stop fingers adapted to engage with the oven frame to limit the downward swinging movement of the door, and housings secured to the oven frame and adapted to enclose said bearing plates and the door journals.
15. 6. In combination with a frame providing a jamb, a door comprising a frame constructed of sheet metal having projecting outer walls, the outer walls of said door frame having associated therewith rigid reinforcing bars, the opposite side bars being of a length adapted to extend beyond the lower edge of the door and the bottom bar having lateral extensions, bearing plates secured to the oven frame and adapted to receive said lateral extensions on the door whereby to mount the door for swinging movement, said downwardly extending portions of the side bars of the door constituting stop fingers adapted to engage with the oven frame to limit the downward swinging movement of the door, an arm rigid with one of said lateral extensions and extending substantially at right angles thereto, and spring means connected with said arm adapted to close said door.
7. In combination with a frame providing a jamb, a door comprising a frame constructed of sheet metal and having outer edge walls, the bottom and side walls having associated therewith rigid bars, the opposite side bars being of a length adapted to extend beyond the lower edge of the door, and the bottom bar having lateral extensions, bearing plates secured to the oven frame and adapted to receive said lateral extensions on the door whereby to mount the door for swinging movement, said downwardly extending portions of the side bars of the door constituting stop fingers adapted to engage with the oven frame to limit the downward swinging movement of the door, an arm rigid with one of said lateral extensions and extending substantially at right angles thereto, spring means connected with said arm adapted to close said door, and housings secured to the oven frame so as to enclose said bearing plates and associated parts.
8. In combination with a frame providing a jamb, a door comprising a frame constructed of sheet metal and bent to provide outer edge walls, said walls having associated therewith rigid reinforcing bars, the opposite side bars being of a length adapted to extend beyond the lower edge of the door and having apertures therein near their lower ends, and the bottom bar having lateral extensions adapted to pass through said apertures in the side bars, bearing plates secured to the oven frame and adapted to receive said lateral extensions on the door whereby to mount the door for swinging movement, said downwardly extending portions of the side bars of the door constituting stop fingers adapted to engage with the oven frame to limit the downward swinging movement of the door, and said lateral extensions each having rigid therewith a sleeve providing a journal adapted to engage in said bearing plate.
9. In combination, an oven frame, a door adapted to engage with said frame to close the oven and comprising a frame formed from sheet metal bent to provide outer inwardly extending flanges, bars rigid with the flanges at the opposite side edges of the door, a bar rigid with the bottom flange, said side bars being apertured and said bottom bar being adapted to extend through said apertures to provide lateral extensions, sleeves fixed upon said lateral extensions to form journals for the door, and plates secured upon the oven frame adapted to coat therewith to form a journal bearing for said journals.
10. In combination, an oven frame, a door adapted to engage with said frame to close the oven and comprising a frame formed from sheet metal bent to provide outer inwardly extending flanges, bars rigid with the flanges at the opposite side edges of the door, a bar rigid with the bottom flange, said side bars being apertured and said bottom bar being adapted to extend through said apertures to provide lateral extensions, sleeves fixed upon said lateral extensions to form journals for the door, plates secured upon the oven frame adapted to coat therewith to form a journal bearing for said journals, an arm rigid with one of said lateral extensions and extending at substantially right angles thereto, and spring means connected with said arm adapted to close the door.
11. In combination, an oven frame, a door adapted to engage with said frame to close the oven and comprising a frame formed from sheet metal bent to provide outer inwardly extending flanges, bars rigid with the flanges at the opposite side edges of the door, a bar rigid with the bottom flange, said side bars being apertured and said bottom bar being adapted to extend through said apertures to provide lateral extensions, sleeves mounted upon said lateral extensions to form journals for the door, plates secured upon the oven frame adapted to coat therewith to form a journal bearing for said journals, an arm rigid with one of said lateral extensions and extending at substantial-

ly right angles thereto, spring means connected with said arm adapted to close the door, and a stop finger rigid with one of said side bars depending from the lower edge of the door and adapted to engage with the oven frame to limit the downward swinging movement of the door.

12. The combination with an oven having a frame defining an opening to be closed, a door adapted to engage with said frame to close said opening, and a hinge structure

comprising a bar fixed to the lower edge of the door having a portion extending outwardly from the side of the door, a sleeve rigid with said lateral extension to provide a journal, and a bearing plate secured to the oven frame and shaped to provide a bearing for said journal. 18

In testimony whereof, I have hereunto set my hand.

RUDOLPH HOFFMAN.
